DESIGN FOR A SHOE

William Bressler, New York, N. Y.

Application May 10, 1934, Serial No. 51,737

Term of patent 3½ years

To all whom it may concern:

Be it known that I, WILLIAM BRESSLER, a citizen of the United States, and resident of New York city, in the county of Kings and State of New York, have invented a new, original, and ornamental Design for a Shoe, of which the following is a specification, reference being had to the accompanying drawing, forming part thereof, in which,

Fig. 1 is a side elevation of a shoe showing my new design; and

Fig. 2 is an elevational view of the other side of the shoe, shown in Fig. 1.

I claim:

The ornamental design for a shoe, substantially as shown.

Dated, May 3, 1934.

WILLIAM BRESSLER.
